CLAIM

The ornamental design for an enclosure system, as shown.

DESCRIPTION

FIG. 1 is a perspective view of an enclosure system, such as for housing electronics hardware and software, according to one preferred embodiment of this invention;

FIG. 2 is a front view of the enclosure system shown in FIG. 1;

FIG. 3 is a side view of the enclosure system shown in FIG. 1;

FIG. 4 is a side view, opposite the side view shown in FIG. 3, of the enclosure system shown in FIG. 1;

FIG. 5 is a top view of the enclosure system shown in FIG. 1;

FIG. 6 is a bottom view of the enclosure system shown in FIG. 1; and,

FIG. 7 is a rear view of the enclosure system shown in FIG. 1.
